UNITED STATES PATENT OFFICE.

WILLIAM J. JOHNSTON, OF PORT HURON, MICHIGAN.

GRAIN-CAR DOOR.

SPECIFICATION forming part of Letters Patent No. 569,923, dated October 20, 1896.

Application filed November 1, 1895. Serial No. 567,643. (No model.)

To all whom it may concern:

Be it known that I, WILLIAM J. JOHNSTON, a citizen of the United States, residing at Port Huron, in the county of St. Clair and 5 State of Michigan, have invented certain new and useful Improvements in Grain-Car Doors; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 This invention relates to car-door fixtures; and it consists in a system of parts and features made and arranged substantially as set forth hereinafter, and as shown in the accompanying drawings, in which—
20 Figure 1 shows a view as from the inside of the car. Fig. 2 shows the door raised, taken from a point at right angles to Fig. 1. Fig. 3 shows a view as from the outside of car. Fig. 4 shows a horizontal section seen 25 from above. Fig. 5 shows a detail view.

The inside face of the car-door frame or stanchion on each side of the door is faced with metal plates. These metal facings are divided into two parts A and A', with groove 30 or slotway B between the parts and widening behind the facings in space C, so as to allow hooks or ears D and D', which hold the door E in place, to move freely up and down in opening and closing the door. Of these 35 plate A extends a space beyond the end of plate A', as shown, A' being so fastened to frame as to be slightly movable and allow variation in width of slot B.

The door is formed of two parts hinged together securely, the upper part F folding down and inward on the lower part E, or the upper part F may be omitted. The lower part E has angle-plates H upon the ends, with one face or edge bent around the end and 45 projecting beyond, so as to enter the slotway B. At the top of this face is the hook or ear D, bent outward, and near the bottom is the hook or ear D', bent inward, the purpose of these ears being to catch back of the plates 50 A and A' and hold the doors securely in place and, with the projecting edge of the angle-plate H running in the slot B, guide

the door up and down. This part E has metal plate or angle-plate R at bottom edge to protect the bottom of the door, and also handles S on outside of door to assist in raising it.

55 The angle-plates H have near the top, middle, and bottom three, or more or less, lugs projecting through the door and parallel with the extending edge of H, forming a bearing 60 with the projecting edge for shaft of rollers K, which enable the door to be easily raised when load is pressing against it from the inside. These rollers and the hooks or ears may be, if desired, on separate parts and the 65 angle-plates partly or wholly omitted.

The part E has staples G or arms at its ends on the upper corners, as shown. The door-frame has dependent hooks L at the top over the plate A' to catch and hold staples 70 G and prevent part E from getting out of frame and to hold part E when swung out and hung up, as shown in Fig. 2. Part E has sliding bolts M on its outer face, arranged in bearings to fasten or lock the door 75 in place.

80 There are dependent hooks N from the car-roof to hold up the lower edge of the door when it is open and swung up on hooks L and staples G.

85 At the point in slot B where the hook or ear D' reaches when the door is hung on hooks L there is a notch or opening O in plate A through which the hook D' can pass.

At the bottom of the door-frames there is 85 a notch or widening of slot B, so as to facilitate the cleaning of grain or other matter from the slot.

When the door is to be opened, it is raised up and the top part F folded back and in on 90 part E. Then part E is pushed up until hooks D escape from the slotway above plate A, when it is pushed inward at the top, so as to bring the staples G into hooks L. Then the lower edge of part E is drawn out, the hooks 95 D' passing through notch O and hung on hook N from the roof. The door is shut by reversing this operation.

Various modifications may be made.

I claim—

100 1. In a grain-car a shutter having a single metal plate on its end bent so as to cover the inner face of the ends of the shutter-timbers and bind them together, and to project into

a slotway in the door-jamb, and bent to one side within such slot to hold the shutter to the jamb, all substantially as set forth.

2. In a grain-car, the combination with the 5 jambs, metallic slotted guides on their inner faces, having near the middle and at the top, cut-away portions, of doors having a flange at the edge entering said slot, and hooks on this flange within the slot, bails on the door, 10 and hooks at the top with which said bails are adapted to engage, the flange-hooks, when the door is suspended, being opposite the cut-away portions.

3. In a grain-car, the combination with the 15 jambs, metallic slotted guides on their inner faces, a door having outwardly-projecting flanges on its edges, with means for preventing detachment except at its upper point, a hinged section at the top of the door, corresponding flanges on this section adapted to enter the slotted guides, and bolts on the door adapted to enter apertures in the jambs.

4. In a grain-car the combination of a shutter-section having ears at the top and bottom 25 bent to the opposite sides, with door-jambs having metal guards with a slotway between arranged to engage with such ears to

hold the shutter in place while free to run up and down and having a space cut out on one side of such slotway at a point arranged so 30 the ear at the bottom can be drawn out inward from the slot to open the door, while the ear at the top of the shutter projecting to the opposite side will pass such point without liability to escape from the slot, substantially 35 as set forth.

5. The combination with the door-jambs, a vertical slotted guide therein, a hooked flange on the end of the door engaging the slot, and friction-rollers for the door on that portion of 40 the jamb which is within and hidden or protected by the flange, for the purpose specified.

6. The combination with the door-jambs having guideways of a door, a roller-bearing, and a guard for said roller carried by the doors 45 to keep them free from the grain at all points of movement.

In testimony whereof I affix my signature in presence of two witnesses.

WILLIAM J. JOHNSTON.
